UNITED STATES PATENT OFFICE

SAMUEL NEWTON HOPE, OF WAUWATOSA, WISCONSIN, ASSIGNOR TO DUDLEY LOCK CORPORATION, OF CHICAGO, ILLINOIS, A CORPORATION OF ILLINOIS

LOCKER LATCH

Application filed October 15, 1930. Serial No. 488,727.

This invention relates to latching mechanisms for closures such as lockers, vaults, safes, cabinets, and the like, in which is employed a vertically movable locking bar for latching the closure member to the body of the locker, etc. The main object of the invention resides in the provision of an improved mechanism for holding the locking bar in raised, inoperative position, while the closure member is in open position, and arranged to be automatically released when the closure member is moved to closed position,— permitting said locking bar to move to latching position. A further object is to provide an improved form of detent which is constructed and arranged for controlling the movement of the locking bar associated with a common type of cabinet or locker now in use, without necessitating any alterations or additions thereto. It consists in certain features and elements of construction, herein shown and described, as indicated by the claims.

In the drawings:

Figure 1 is a face view of a locker equipped with latching mechanism embodying the present invention.

Figure 2 is an enlarged view looking at the inner side of the closure and frame, with the side walls of the locker omitted.

Figure 3 is a transverse section taken substantially as indicated at line 3—3 on Figure 2.

Figure 4 is an enlarged fragmentary horizontal section taken as indicated at line 4—4 on Figure 2.

Figure 5 is an enlarged vertical section taken at line 5—5 on Figure 2, showing the improved latching mechanism in position ready to be actuated as the closure is about to be moved to its final closing position.

Figure 6 is a sectional view similar to Figure 5, showing the position of the detent and locking bar when the closure is in closed position.

Figure 7 is an enlarged fragmentary view at the inner side of the closure showing the locking bar in latching position.

Figure 8 is a perspective detail view of the improved form of detent embodying the invention.

Figure 9 is a vertical section showing another form of securement of the detent to the closure.

For the purpose of illustration the present invention is shown embodied in a common type of locker or cabinet now in use. In the construction herein shown the locker includes a body or frame, 1, formed with an opening, 2, which is controlled by a closure member or door, 3, hinged at 4 to said frame for swinging on vertical axes. The body or frame of the locker is formed of angle and channel members to insure rigidity and ample strength, which members are connected to suitable side walls not shown. The closure member or door, 3, which is preferably formed of sheet metal, has its free edge folded inwardly to form a flange, 5, extending at right angles to the plane thereof, and then continues into a series of bends for reinforcing this free edge of the closure, and providing a pair of spaced walls, 5^a, forming a longitudinally extending guideway, 6, in which is mounted a vertically movable locking bar, 7.

The locking bar, 7, is preferably of U-shape cross section with the open side facing the closure panel, as seen in Figure 4, and has certain portions of its legs intermediate its length cut back and flared outwardly, as indicated at 7^a, in the drawings, for engagement beneath correspondingly recessed shoulders, 9, formed in the adjacent guide walls, 5^a, so as to provide guidance for the locking bar throughout its range of vertical movement, while at the same time holding it captive. Rigidly secured to said locking bar is an exteriorly accessible handle, 10, which, as shown, is provided with lugs, 11, which

register with a fixed lug, 12, on the frame, 1, which lugs are provided with apertures, 11^a and 12^b, respectively, for receiving the shackle of a padlock in case it is desired for locking the locking bar in latching position. However, I prefer employing a cabinet lock as indicated at A, connected through a bell crank lever, B, to the locking bar, for controlling its movement.

The locking bar, although not necessarily, is preferably arranged to latch the closure to the body or frame at a plurality of vertically spaced points, and for this purpose the closed end or portion intermediate the legs of the U-shape locking bar which extends parallel to the plane of the closure, is provided with a plurality of vertically spaced apertures, 13, which are adapted to register with correspondingly located keepers, 15, rigidly secured to the frame or body, 1, of the locker. These keepers, as will be seen in Figure 5, are formed to provide latching shoulders, 16, so that when the keepers have entered the cooperating apertures of the locking bar, and said locking bar is then permitted to move downward, it engages behind the shoulders, 16, of the keepers for positively latching the closure to the body. To obviate noise and cushion the impact of the locking bar incident to its movement to and from operative position, I provide plugs or blocks, 17, of resilient material, such as rubber, frictionally secured at the upper and lower ends respectively of the closure between the transverse flanges, 3^a and 3^b, at the top and bottom respectively of the closure, and the shortened ends, 5^b and 5^c, respectively, of the reinforced folds, 5^a, at the free edge of the door. Thus, when the locking bar is raised the upper end thereof engages the block of resilient material at the top of the closure, and likewise when the bar is moved down to its lower or operative latching position the lower end thereof engages the block of resilient material at the bottom of said closure, as seen in Figure 6.

To reduce the number of manual operations incident to the opening and closing of the closure members or doors in structures of this character, there is provided means for holding the locking bar in raised position during the time that the closure member is in open position, which means is also arranged to automatically release the locking bar to permit it to move to operative or latching position when the door is moved to its closed position. This means includes a removable, resilient detent member, 21, formed with two angularly related legs, 21^a and 21^b, respectively, disposed within and, preferably as shown, adjacent the bottom of the U-shape locking bar and anchored against the panel by an extended spring tang, 22, which is frictionally held in the lower corner of the closure against the flange, 3^b, by the bottom

block, 17, of resilient material, as seen in Figure 5 of the drawings. This detent member is so designed that normally the upper end of the leg, 21^a, is urged in the direction to extend through the lowermost aperture, 13, of the locking bar, with its upper edge engaging the shoulder, 13^a, which forms the upper edge of said opening, 13, in the locking bar and thereby hold said locking bar in raised, inoperative position. The other leg, 21^b, of the detent member is of substantial width and normally lies in registration with the lowermost aperture, 13, in the locking bar, so that as the closure member is moved to closed position, the bottom keeper, 15, enters said lowermost opening, and impinges against the leg, 21^b, of the detent, depressing it so as to move the leg, 21^a, out of engagement with the shoulder, 13^a, of the locking bar, as seen in Figure 6, and thereby permitting said locking bar to move into latching engagement in back of the shoulders, 16, of the keepers. It may be understood that the locking bar is freely movable in its associated guides, 5^a, at the free edge of the closure, and normally the locking bar is permitted to drop by gravity into latching position, as soon as it is released by the detent, 21.

This construction is of decided advantage, as will be apparent, since the detent is removably secured in place merely by frictional engagement with the block of resilient material, which arrangement dispenses with alteration or additional structure to permit its embodiment in this particular form of commercial cabinet or locker that is now in use. Thus this improvement may be readily applied to cabinets and lockers that have been in use for some time.

Figure 9 illustrates a slightly modified construction in which the detent, 21, is permanently connected to the closure member by a rivet, 24, securing the tang, 22, to the lower transverse flange, 3^b, of the closure member.

I claim:—

1. In a locker or the like having an opening, a closure therefore, with a keeper adjacent the opening and a vertically movable locking bar on the closure having a flange portion extending parallel to the plane of the closure and spaced therefrom, said flange having an opening to receive the keeper, the combination of a plug of resilient material held frictionally and removably in a pocket formed in said closure in position for cushioning the impact of the locking bar at one limit of its movement, and a spring detent member having a foot piece disposed in said pocket and anchored by the resilient plug therein, said detent engaging one edge of the opening in the flange of the bar for upholding it at the upper limit of its movement, and being formed for encounter by the keeper, whereby the latter disengages the detent from

the bar automatically as the closure approaches closed position.

2. In a locker or the like having an opening, a closure therefor, with a keeper adjacent the opening and a vertically movable locking bar on the closure having a flange portion extending parallel to the plane of the closure and spaced therefrom, said flange having an opening to receive the keeper, the combination of a plug of resilient material held frictionally and removably in a pocket formed in said closure in position for cushioning the impact of the locking bar at its lower limit of movement, and a detent member having a foot piece disposed in said pocket and anchored by the resilient plug therein, said detent extending transversely from the foot piece and formed remote therefrom to engage the upper edge of the opening in the locking bar flange for retaining the latter at its upper limit, and being formed for encounter with the keeper when the latter enters the opening, whereby the foot piece is rocked against the resilient plug and the remote end of the detent is disengaged from the locking bar.

SAMUEL NEWTON HOPE.
